UNITED STATES PATENT OFFICE.

GEORGE MILES LEE, OF LITTLE FALLS, NEW YORK.

ELECTRIC SPEED-GOVERNOR FOR WATER-WHEELS.

SPECIFICATION forming part of Letters Patent No. 392,679, dated November 13, 1883.

Application filed July 30, 1883. Serial No. 281,421. (No model.)

To all whom it may concern:

Be it known that I, GEORGE MILES LEE, a citizen of the United States, residing at Little Falls, in the county of Herkimer and State of New York, have invented a new and useful Improvement in Electric Speed-Governors for Water-Wheels, of which the following is a specification.

My invention relates to an improvement in electric speed-governors for water-wheels; and it consists in the peculiar construction and combination of devices, that will be more fully set forth hereinafter, and particularly pointed out in the claims.

In the accompanying drawings, Figure 1 is an elevation, partly in section, of an electric speed-governor embodying my improvements. Fig. 2 is a top plan view of the mechanism for controlling the gate. Fig. 3 is an end elevation of the same. Fig. 4 is a vertical end elevation of the governor apparatus.

A represents a base plate or frame from which, at a suitable distance apart, rises a pair of vertical standards, B, which have bearings C in their upper ends. Journalized in the said bearings is a horizontal shaft, D, which is prevented from moving endwise by means of collars E, that are secured thereto by set-screws F and bear against opposite ends of one of the bearings C.

Near one end of the shaft D is a worm, G, which rotates with said shaft and engages a worm-wheel, H, that is secured to a vertical shaft, I. The latter is adapted to be secured to and adapted to move a water-gate, (not shown,) so as to cut off and to regulate the supply of water to the water-wheel. (Not shown.)

Secured to the center of the shaft D is a collar, K.

L M represent a pair of pulleys, which are loosely mounted on the shaft D and have their hubs bearing against opposite sides of the collar K. On the outer sides of said pulleys, and preferably formed integrally therewith, are friction-pulleys N O, respectively. Collars P are rigidly secured to the shaft D, and bear against the outer sides of the pulleys L M and serve to prevent the latter from moving longitudinally on the shaft.

R represents a friction-pulley, which is feathered on the shaft D and is adapted to engage the pulley N. The hub of said pulley R

is provided with an annular groove, S, in which is fitted an annular rim or collar, T.

U represents a friction-pulley, which is similar to the pulley R, is likewise feathered to the shaft D, and is adapted to engage the friction-pulley O. In other words, the friction-pulleys constitute clutch devices, which are adapted to lock the pulleys L M to the shaft D. The hub of the friction-pulley U has an annular groove in which is fitted an annular collar, V.

W represents a horizontal arm, which is bolted to and projects inward from one of the standards B, and X represents a similar arm, which projects from the other standard B. An armature-lever, Y, is fulcrumed centrally to the bifurcated inner end of the arm W, and has its upper end bifurcated or forked and pivotally connected to the collar T. A similar armature-lever, Z, is fulcrumed to the arm X and has its bifurcated upper end pivotally connected to the collar V.

A' represents an electro-magnet, which is mounted on the base A, and is adapted to attract the lower end of the armature-lever Y.

B' represents a similar electro-magnet, which is adapted to attract the lower end of the armature-lever Z. Retracting-springs C' and D' are connected to the lower ends of the armature-levers Y and Z, respectively, and to arms E', which project from the base at a point midway between the electro-magnets.

The mechanism hereinbefore described constitutes the rack-levers for controlling the gate. I will now proceed to describe the governor apparatus proper.

F' represents a suitable inclosing-case, which has a shelf or ledge, G', at a suitable distance from its bottom. Secured on the center of the said shelf or ledge is a standard, H', which has a horizontal arm or sleeve, I'. Swiveled in the said standard is a vertical sleeve, K', which has a miter-wheel, L', that engages a similar wheel, M', secured to the inner end of a shaft, N', that is journaled in the sleeve or arm I'. To the outer end of said shaft, which projects through the rear side of the inclosing-case, is keyed a pulley, O', which is rotated by an endless belt from a counter-shaft, (not shown,) which is geared to and operated by the water-wheel.

P' represents a vertical governor-shaft, which

is feathered in the sleeve K', and is thereby adapted to rotate with the said sleeve and to play vertically therein. To the upper end of the said governor-shaft is secured a head or 5 collar, R'.

S' represents a pair of flat springs, which connect the head or collar R' with the upper end of the sleeve K', and are arranged on diametrically - opposite sides of the governor- 10 shaft. To the central portion of the said springs are secured governor-balls T'.

U' represents a vertically - movable rod, which has its upper end secured to the vertically-movable governor-shaft, and passes through 15 a bearing, V', on the center of the base of standard H', and through an opening in the shelf or ledge G', and to the lower end of the said rod is secured a disk, W', which is made of non-conducting material.

20 X' represents a hanger, which depends from the shelf G' at a distance from the rod U'.

Y' represents a similar hanger, which depends from the said shelf and is arranged much nearer the said rod U'. A vertically- 25 adjustable conducting - screw, Z', engages a bearing in the shelf G', and extends through the same at a point between the rod U' and the hanger X', and is provided at its lower end with a platinum contact-point. A similar adjustable conducting-screw, A², engages a bearing in the shelf and passes through the same at a suitable distance from the outer side of 30 the hanger Y', which is likewise provided with a platinum point at its lower end.

35 It will be observed by reference to Fig. 4 that the hanger Y' is between the rod U' and conducting-screw A², and that the conducting-screw Z' is between the rod U' and the hanger X'.

40 B² represents a contact-lever or circuit-closer, which is fulcrumed at a suitable distance from its outer end to the lower end of the hanger X', and has its longer end bearing against the lower side of the non-conducting 45 disk W', the said circuit-closing lever being normally maintained in this position by a spring, C².

D² represents a similar circuit-closing lever, which is fulcrumed at a slight distance from 50 its inner end to the lower end of the hanger Y', engages the non-conducting disk W' with its shorter inner end, and is held normally in this position by a spring, E², with which it is provided. The said contact-levers D² and B² 55 are provided with platinum points or studs which are adapted to engage the platinum points of the conducting-springs, and arranged under the outer end of the contact-lever D² is a stop-screw, F', which is supported by a 60 bracket, G².

H² represents a bracket depending from the lower side of the shelf or ledge G', to the lower end of which is pivoted an intermediate point of the safety-lever K², one end of which normally bears against the hook-shaped contact-point L², and the free end of this safety-lever projects over the non-conducting disk W'. 65

The pulleys L M are connected to a counter-shaft, which is geared to the water-wheel, and are rotated thereby in opposite directions at 70 all times when the water-wheel is in operation.

The terminals of the coils of the electro-magnet A' are connected with the hanger X' and screw Z' by means of conductors a a'. At 75 an intermediate point of the conductor a' is introduced a battery, c, and between the battery and the screw Z' the conductor is divided, and the free ends thus formed are connected, respectively, to the bracket H² and the contact-point L², and whereas the lever K² is normally in contact with the contact-point L² the 80 circuit is usually intact at this point. The terminals of the coils of the electro-magnet B' are connected to the hanger Y' and the conducting-screw A² by the conductors b b'. The conductor b' is divided at a suitable point, and its ends are connected to the wire a', respectively, between the electro-magnet A' and the battery c and between the contact-point L² and 85 the screw Z'. Thus it will be seen that the battery c is in the circuit a a' and also in the circuit b b', and the safety devices, which comprise the lever K² and the point L², are also in both circuits. The two wires which extend from 90 the battery are, in effect, branched at the points d and d', the wires proceeding from the branch d extending, respectively, to the magnets A' and B', and the wires proceeding from the branch d' extending, respectively, to the contact-screws A² and Z', while the safety device 95 is introduced at an intermediate point of one of the wires which extend from the battery and between the battery and the branch d'. When the water-wheel is running at normal speed, the 100 governor-shaft is maintained at such an elevation by the governor-balls as to cause the disk W' to support the circuit-closers B² and D² out of contact with the conducting - screws, and thereby open both the electric circuits a and 105 b. When the speed of the water-wheel is increased to an undesirable extent, the governor-balls are moved from each other by centrifugal force, and the governor springs or arms serve to lower the governor-shaft, so as to cause the 110 disk W' to depress the shorter arm of the circuit-closer D², to cause the same to come in contact with the screw A², and thereby close the circuit b, which obviously passes through the safety device when the magnet B' is excited 115 and caused to attract the lower end of the armature - lever Z, and said lever being connected to the friction pulley or clutch to engage the wheel M and lock the same to the shaft D and rotate the shaft I, and thereby partly close 120 the water-gate and hence reduce the supply of water to the water-wheel. When the speed of the water-wheel decreases, the governor-balls cause the governor-shaft to move upward, as will be readily understood, so as to raise the 125 inner end of the circuit-closer B² and cause the same to come in contact with the screw Z', and thereby close the circuit a. This causes the electro-magnet A' to be excited and attract the

armature-lever Y, so as to engage the friction pulley or clutch R with the pulley L, which is running in the opposite direction from the pulley M, and thereby lock said pulley L to the shaft D, and consequently rotate the said shaft D in the opposite direction and cause the worm-gear G H to turn the shaft I, so as to open the water-gate to an increased extent, and thereby increase the supply of water to the water-wheel. If, however, during the operation of the water-wheel the belt should slip from the pulley which operates the governor or should break, or any of the other parts of the device should give away, the governor-rod will be raised forcibly by the action of the spring S', and the disk W' will strike the free end of the safety-lever K', thereby breaking the circuit and maintaining it open. It is obvious that the upward movement of the governor-rod will thus break both the circuits a a' and b b'.

It will be observed from the above description, taken in connection with the accompanying drawings, that only one battery is employed to operate both keys or circuit-closers, and when one of the circuits (for instance, the circuit a a') is closed the other circuit is entirely unaffected, and the current passes through the electro-magnet A' and the safety device in the manner described.

Having thus described my invention, I claim—

1. The combination, in an electric governor, of the shaft D, the loose pulleys revolving in opposite directions thereon, the clutch devices adapted to lock the said pulleys to said shaft, the armature-levers to operate said clutch devices, the governor having the vertically-movable rod, the electric circuits having the electro-magnets adapted to attract the armatures, and the circuit-closers adapted to be operated by the governor-rod, substantially as described.

2. The combination of the shafts D I, the gearing connecting the said shafts, the loose pulleys on shaft D, the clutch devices adapted to engage said pulleys and to lock the same to the said shaft, the armature-levers connected to said clutch devices, the electro-magnets to attract said armature-levers, the conductors and batteries, one or more, connected to said electro-magnets, the circuit-closers in circuit therewith, and the centrifugal governor having the movable rod adapted to engage and operate the said circuit-closer, substantially as described.

3. The combination of the centrifugal governor having the vertically-movable rod U', the conducting-screw Z', the pivoted circuit-

closer B', adapted to make contact with said screw and engaging the rod U', the circuit-closer D', also engaging the said rod, and the contact-screw A', adapted to be engaged by the said circuit-closer, substantially as described.

4. The combination of the shaft D, provided with the loose pulleys L M, the clutch devices to lock said pulleys to the shaft, the armature-levers connected to the said clutch devices, the electro-magnets to attract the armature-levers, the conductors and batteries connected to the said electro-magnets, the circuit-closers in circuit therewith, the safety device comprising the lever K', and the contact-point L', in circuit with the batteries, and the governor provided with a movable rod adapted to operate the circuit-closers and the cut-out lever K', substantially as specified.

5. In an electric governor, the combination of the shaft D, provided with the pulleys, the clutch devices to lock the said pulleys to the shaft, the armature-levers to operate the clutch devices, the electro-magnets to attract the armature-levers, the circuit-closers connected by suitable conductors with the electro-magnets, the battery provided with branched wires which are connected, respectively, to the electro-magnets and the circuit-closers, the safety device in circuit with both electro-magnets, and the centrifugal governor provided with a movable rod to engage and operate the circuit-closers and the safety device, substantially as specified.

6. In an electric governor, the combination of the shaft D, provided with loose pulleys, the clutch device to lock the pulleys to the shaft, the armature-levers to operate the clutch devices, the circuit-closers, the electro-magnet A', provided with the conductors a a', which are connected to one of the circuit-closers and also include in the circuit a battery, c, the electro-magnet B', provided with the conductors b b', which are connected to the other circuit-closer, the conductor b' being intercepted by the wires proceeding from the battery b, whereby the said battery is included in the circuit therewith, and the centrifugal governor provided with a movable rod which is adapted to engage and operate the circuit-closers, substantially as and for the purpose specified.

In testimony that I claim the foregoing as my own I have hereto affixed my signature in presence of two witnesses.

GEORGE MILES LEE.
